UNITED STATES PATENT OFFICE.

EDWIN W. McCUTCHEON, OF PORTSMOUTH, NEW HAMPSHIRE.

STATION OR STREET INDICATOR.

No. 911,059.

Specification of Letters Patent.

Patented Feb. 2, 1909.

Application filed April 23, 1906. Serial No. 313,159.

To all whom it may concern:

Be it known that I, EDWIN W. McCUTCHEON, a citizen of the United States, residing at Portsmouth, in the county of Rockingham 5 and State of New Hampshire, have invented a new and useful Station or Street Indicator Designed to be Used in Railway-Cars, of which the following is a specification.

My invention is in the form of a set of 10 rolls, having a printed roll-sheet, which, in connection with a lettered sign, indicates stations with changes or transfers (or streets if printed and lettered therefor,) when the rolls are properly manipulated.

15 The object of my invention is to give railway car passengers an easy and continuous means of ascertaining by visual evidence, the next station, street or stop, with its changes or transfers, as the car runs from one station, 20 street or stop to another while *en route*. I attain this object by the mechanism illustrated in the accompanying drawings, in which—

Figure 1, is an elevation, showing the indicator as the car is approaching a station; Fig. 25 2, is a partial elevation, showing the indicator as the car is arriving at a station; Fig. 3, is a view of a hook used to manipulate the rolls; Fig. 4, is an elevation, the doors being 30 open, showing the indicator as the car is approaching a station where a change is made; Fig. 5, is a section on line 5—5, of Fig. 4; Fig. 6, a portion of the roll-sheet to show the 35 method of printing the same.

Similar letters refer to similar parts throughout the several views.

The uprights or standards A A, together with the bottom board B, and the top board C, constitute the framework of the indicator. 40 The indicator may be secured to the ceiling of a car by the hangers I I, or by any other suitable hangers, as those shown in the drawings form no part of my invention. Both sides of the indicator, (A to A), are to all intents identical with that shown in Fig. 1.

The indicator is designed to be hung midway of a car, the parallels of the frame B C, over, and at right angles with the aisle, or crosswise of it, so that either side of the indicator can be readily viewed; it may, however, be hung at any convenient place. The double doors DE DE, respectively the same on opposite sides of the indicator, when closed, serve to lessen the exposure of the 50 printed roll-sheet G, as illustrated in Fig. 1,

and, when open, as illustrated in Fig. 4, to expose the aforementioned roll-sheet in its entire extension on rollers f f and H. The roll-sheet G is secured at either end to rollers f f.

The partial exposure of the printed roll-sheet G allows the name of one station to be exhibited at a time, as in Fig. 1, and the entire exposure of the extension of said roll-sheet allows the space necessary to exhibit the names of changes or transfers, also, as 60 illustrated in Fig. 4. The doors DE DE are secured by buttons and cleats e e (see Fig. 1). The roll-sheet G is printed on one side with the succession of the names of the stations, (with such changes or transfers as 65 are incident thereto) for a particular run, in the manner illustrated in Fig. 6, every name of a station, change or transfer, being printed twice thereon. This method of printing the roll-sheet G allows the name of any station, 70 or stations, printed thereon to be exhibited on either side of the angle formed by said roll-sheet in its extension on rollers f f and H, and, therefore, on opposite sides of the indicator simultaneously.

The printed roll-sheet G may be rolled over roller H until the name of any station to be shown appears on opposite sides of the indicator, over tops of doors DE, DE, respectively, providing no changes are shown 75 therewith, and, in connection with the lettered or printed sign F, referred to herein-after, it indicates the next station as the car approaches such while *en route*. The printed roll-sheet G may be rolled from one roller f 80 to the other, alternately, over roller H. For clear comprehension of the movement of roll-sheet G, see Fig. 5.

When the car is approaching a station where a change is made, the doors DE DE 85 may be opened and the indicator then indicates the next station with changes or transfers as illustrated in Fig. 4.

The rollers f f are fitted in standards A A and run freely. The rollers f f are iron or metal, the weight of which is expressly designed to tighten, to make roll well, and to arrest, or prevent unwinding of the roll-sheet G as it is manipulated. The iron or metal winding rollers f f make the roll-sheet 100 G stop well at any point and are in the interest of simplicity, allowing easy operation of the device, and making unnecessary, 105 springs, brakes, tension rollers, or other devices to control the roll-sheet.

The roller H is reduced in diameter at either end, and is fitted in standards A A, see Figs. 1, 2, 4 and runs freely, serving to extend roll-sheet G from rollers f f, and to allow free movement of said roll-sheet when rollers f f are manipulated. The disks or finger-wheels K K, having teeth, are secured near one end of each roller f f, overlapping each other, and projecting through notched doors E E (when the doors are closed) on opposite sides of the indicator.

The hook L may be used to turn the rollers f f, by hooking it into the teeth of either of wheels K K where such project through doors E E, see Fig. 1, and pulling downward, thus turning one roller f and rolling or winding roll-sheet G from one roller f to the other over roller H at will. The disks or finger-wheels K K may be manipulated by hand, also, if within reach. The hook L may be used to turn buttons e e, and open the doors DE DE by means of knobs d d, also.

The quadrangular sign F turns on pivots c c and is lettered on opposite sides, (the remaining sides being blank) in the manner illustrated in Figs. 1, 4, to correspond to, and to be read in connection with, the names of the stations printed on the roll-sheet G as said names of stations are successively rolled into view on opposite sides of the indicator.

A cord is secured to one end of sign F at a, see Fig. 5, which passes downward inside and close to one standard A, through a hole in bottom board B, as illustrated in dotted lines, whence it returns in similar fashion and is secured to sign F at b. The loop thus formed extends below the indicator, see Figs. 1, 4, 5, and by means of it the sign F,

balanced on pivots c c, may be turned so as to show either its lettered or its blank sides.

The indicator as illustrated in the accompanying drawings is shown as lettered and printed for steam cars, I therefore, have omitted the use of the word street in the detailed part of this specification as tending to confuse. To make the indicator suitable for a street car is merely a matter of proper lettering on sign F and of printing on roll-sheet G. The method of using the indicator may be as follows: At the beginning of a run, the indicator may be set as illustrated in Fig. 1, and when the car is arriving at a station thus indicated, the sign F may be turned blank, see Fig. 2, then as the car resumes its run, said sign may be turned to show its lettered sides again, and another name of a station may be rolled into view and so on to the end of the run. One indicator may be taken down and another substituted, if suitable hangers are provided.

What I claim as my invention and desire to secure by Letters Patent, is—

In a station or street indicator, the combination of two lower winding rollers, said rollers being made heavy or loaded as gravity winding rollers, a roll-sheet attached at its ends to said winding rollers and having station or street names marked thereon, a third upper roller over which said roll-sheet passes all substantially as and for the purpose specified.

In testimony whereof I have signed my name to this specification in the presence of two subscribing witnesses.

EDWIN W. McCUTCHEON.
